UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

QUICK-BREAK SWITCH.

Application filed May 19, 1923. Serial No. 640,093.

To all whom it may concern:

Be it known that I, BENJAMIN E. GETCHELL, a citizen of the United States of America, residing at Plainville, county of 5 Hartford, State of Connecticut, have invented a new and useful Quick-Break Switch, of which the following is a specification.

My invention relates particularly to 10 double throw knife blade switches which are usually enclosed.

The main object is to provide a simple 15 but reliable and effective construction of this type which will break either of two circuits with a snap action.

I have shown the invention as applied to 20 a more or less typical or standard form of double throw switch having one or more blades connected by a cross bar which carries a pair of pivoted jaws or arms engaged 25 by the opposite sides of the operating crank and connected by a spring. The construction and operation will be understood from the following specification.

25 Figure 1 is a perspective view of one form of construction embodying the improvements of my invention, and showing the parts in the open circuit position.

30 Figure 2 is a side view and partial section of the switch proper showing the parts in the closed circuit position and indicating in dot-dash lines the relative movement of certain of the parts at the beginning of the opening movement.

35 Figure 3 is a perspective view showing the principal parts separated.

Figures 4 and 5 are detail views of a modified form of construction.

Each switch member 6 in the form shown 40 has two blades extending substantially at right angles to each other and pivotally supported by posts 7 in position to be swung so as to engage either contact 8 or contact 9, depending upon which circuit is to be completed. The switch parts are preferably mounted on an insulating base 10 within a box or receptacle 11. The movable switch members are preferably connected by a cross-bar 12 of insulating material. The switch is intended to be operated by any suitable form of external handle 13 and internal crank 14 suitably supported in a box.

The connection between the crank 14 and

the movable switch members is effected through movable members 15 and 16 suitably secured to the cross-bar 12 and resiliently held in position to be engaged by the crank 14. For simplicity and convenience, a single spring 17 connecting the members 15 and 16 serves to cooperate with both members 15 and 16. A bracket 18 secured to the cross-bar 12, for instance by means of a bolt 19, serves as a support for the arms 15 and 16 which are pivoted to the lugs 20 and 21. The spring 17 serves to press the arms 15 and 16 against the sides of the cross-bar 12 so that the cross-bar serves as a stop for the arms 15 and 16 as they move toward each other. The bracket 18 has preferably lugs 22 and 23 which serve as stops to limit the 55 outward swinging movement of the arms 15 and 16. The engagement of the lugs 20 and 21 with the sides of the cross-bar serves to aid in supporting the bracket on the cross-bar in its proper position and prevent displacement.

When it is desired to close the circuit by moving the switch member from the position of Figure 1 to the position of Figure 2, the handle 13 is thrown to the right so that the 60 crank 14 engages the arm 15 and thus transmits action to the cross-bar 12 and attached switch members. When the switch member 6 engages the stationary contact 8, the frictional resistance retards the parts until the 65 arm 15 engages the lug 22. A positive connection is thus effected from the crank 14 to the switch member, which enables the operator to forcibly close the switch. As soon as the switch handle is released, the spring 70 17 will throw the crank 14 and handle back to the position shown in full lines of Figure 2. To open the circuit the handle 13 is moved toward the left and the friction of the contact jaws 8 is sufficient to hold the 75 switch member stationary until the crank 14 has moved the arm 16 far enough to the left to engage the lug 23. The operating force is thus transmitted positively to start the opening movement of the switch. As 80 soon as the switch member 6 leaves the contact 8 it snaps away quickly under the impulse of the spring 17 even though the handle should be momentarily held after the movement had started. In other words, 85 the mechanism produces a quick-break which

cannot be stopped by the operator when once it is started. The operation of closing and opening the circuit between the switch member 6 and contact 9 is effected in the same manner as will be obvious from an inspection of the drawings.

In Figures 4 and 5 I have shown a somewhat different form of construction which however operates in the same manner as the one above described. The bracket 18' is secured to the cross-bar 12 in this case by means of two screws 19', and the lugs 20' and 21' serve as pivotal supports for the arms 15' and 16' respectively. The ends of 15 these arms are offset and the connecting spring 17' lies between them. The cross-bar 12 serves as an inner abutment to the arms 15' and 16'. The outward swinging movement of the arms is limited by the extensions 24 and 25 which are adapted respectively to abut against the underside of the bracket 18' when the arms are swung outwardly by the crank 14. Such a construction has certain advantages under some circumstances. Separate stops such as 26 and 27 may be provided if desired for limiting the throw of the handle or operating crank.

In both forms herein shown there is a bracket carrying two pivoted arms connected by a single spring for affording equal tension in both directions and having stops to limit the relative movements of the arms in both directions. When either arm is moved it applies added tension to the other arm.

It should be understood that other alterations and modifications may be made within the spirit and scope of my invention.

I claim:

1. In a quick break switch, a double throw switch member, two movable arms carried thereby, abutments therefor, yielding means for holding said arms in the normal position of rest, and a crank adapted to engage either of said arms to operate said switch member.
2. In a quick break switch, a movable switch member, arms pivotally secured thereto, a spring connecting said arms and an operating crank for engaging said arms.
3. In a quick break switch, a pivoted switch member, two arm members movably connected therewith, resilient means for holding said members in their normal positions of rest, a crank for alternatively engaging said arms to operate said switch member.
4. In a quick break switch, stationary switch contacts, a double throw switch member pivotally mounted between said contacts and adapted to engage either one of said contacts, an operating crank and two resiliently connected arms coacting between said

crank and said movable switch member to open or close the circuit.

5. A quick break switch comprising stationary switch jaws, a double throw switch member mounted to move between said jaws, an operating crank, pivoted arms mounted to cooperate with said movable switch member and said crank and spring means for operating said arms.

6. A quick break switch comprising stationary contacts, a movable switch member, a bracket carried thereby, arms pivotally mounted on said bracket, spring means for normally holding said arms against said bracket and an operating crank interposed between said arms.

7. A double throw quick break switch comprising a movable switch member, stationary contacts adapted to be engaged thereby, a bracket movable with said switch member having outer and inner stops, spring pressed arms mounted to move between said stops and an operating crank cooperating with said arms.

8. A quick break switch comprising stationary and movable members, a cross bar connecting the movable members, arms pivotally mounted on opposite sides of said cross bar, spring means for normally holding said arms against said cross bar and an operating crank having a portion interposed between said arms.

9. A quick break switch comprising movable switch members a cross bar connecting said members, arms movably carried by said cross bar, resilient means for pressing said arms against the opposite sides of said cross bar, stops for limiting the outward movement of said arms and an operating member interposed between said arms.

10. As an article of manufacture, a self contained snap action device for a double throw electric switch comprising a bracket, arms pivotally carried by said bracket, a spring connecting said arms and normally holding them against said bracket and coacting abutments integral respectively with said bracket and said arms for limiting the outward movement of said arms.

11. In a double throw switch, a quick break switch including a bracket, two arms pivotally carried thereby, stops therefor, and a single spring connecting said arms.

12. In a double throw switch, a quick break mechanism including an insulating support, two arms pivotally carried thereby, a single spring connecting said arms, and an operating member movable between said arms.

BENJAMIN E. GETCHELL.
